[57] CLAIM

The ornamental design for a cutting guide, as shown and described.

DESCRIPTION

FIG. 1 is a perspective view of a cutting guide showing my new design;

FIG. 2 is a top plan view;

FIG. 3 is a bottom plan view;

FIG. 4 is a left side elevational view, which is a mirror image of the right side; and,

FIG. 5 is a front elevational view, which is a mirror image of the rear elevational view.

No claim is made to the phantom material, hand and scissors, as they are shown for environmental purposes only.
